Primary Examiner — Omeed Agilee*Assistant Examiner* — David Truong(74) *Attorney, Agent, or Firm* — Dickinson Wright PLLC**CLAIM**

The ornamental design for a ring box with Santa Claus, as shown and described.

DESCRIPTION

FIG. 1 is a perspective view of a ring box with Santa Claus showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings depict portions of the ring box with Santa Claus that form no part of the claimed design.
